UNITED STATES PATENT OFFICE.

FREEMAN N. YOUNG AND FRANCIS E. THOMPSON, OF BOSTON,
MASSACHUSETTS.

DESIGN FOR A PACKING-CASE.

SPECIFICATION forming part of Design No. 38,838, dated January 1, 1901.

Application filed September 27, 1900. Serial No. 31,335. Term of patent 14 years.

To all whom it may concern:

Be it known that we, FREEMAN N. YOUNG and FRANCIS E. THOMPSON, citizens of the United States, residing at Boston, in the county of Suffolk, State of Massachusetts, have invented and produced a new and original Design for Packing-Cases, of which the following is a specification, reference being had to the accompanying drawing, forming a part thereof, in which the figure is an isometrical perspective view of the packing-case, showing our new design.

As shown in the drawing, the case is rectangular; and the leading feature of our design consists in the representation on one vertical face thereof of a plurality of bottles arranged in rows and in perspective to give the appearance at a distance that the side wall of the case had been removed and the contents exposed. As illustrated, a cen-

tral bottle of the group has the wrapper removed. The dovetailing of the box-walls is represented at the vertical edges and the top and bottom as being of plain boards.

The salient feature of the design consists in the representation on a wall of a packing-case of the contents of such case in such manner as to convey the impression to the eye of the observer that such wall has been removed and the true contents exposed. 25 30

Having thus described our invention, what we claim is—

The design for a packing-case substantially as herein shown and described.

FREEMAN N. YOUNG.
FRANCIS E. THOMPSON.
